J. J. MORRISON, OF ATLANTA, ASSIGNOR TO HIMSELF AND V. A. GASKELL, OF FULTON, GEORGIA.

Letters Patent No. 87,505, dated March 2, 1869.

IMPROVED COTTON-PRESS.

The Schedule referred to in these Letters Patent and making part of the same.

To all whom it may concern:

Be it known that I, J. J. MORRISON, of Atlanta, in the county of Fulton, and in the State of Georgia, have invented certain new and useful Improvements in Cotton-Press and Lint-Room; and do hereby declare that the following is a full, clear, and exact description thereof, reference being had to the accompanying drawings, and to the letters of reference marked thereon.

The nature of my invention consists in the construction and general arrangement of a "cotton-press and lint-room," whereby the double operation of ginning and pressing the cotton go on at the same time.

In order to enable others skilled in the art to which my invention appertains, to make and use the same, I will now proceed to describe its construction and operation, referring to the annexed drawings, which form a part of this specification, and in which—

Figure 1 is a side elevation, and

Figure 2, a longitudinal vertical section.

The machine consists of a hacking-box, A, attached to the side of the house which contains the cotton-gin on the second floor, the upper part of the packing-box extending up a suitable height on the second floor; or rather a frame or box, B, is added to the top of the packing-box, which addition extends up on the second floor.

By means of this arrangement, the lint, as soon as ginned, is immediately blown into the packing-box.

The cotton is then compressed by means of the follower or compressor C, which is driven down upon it by means of the crank D, by successive strokes about every half minute, this crank being connected with the compressor by means of a rope, a, passing over pulleys b b, as shown in fig. 1.

While the compressor is down, the cotton is prevented from going over it into the box, by means of a sash, E', which rests on top of the packing-box, and moves up with the compressor when elevated.

The sash E', which moves in grooves on the frame B, is simply a plain board, occupying half the open space between the bottom of the compressor, when elevated, and the top of the packing-box A.

It will be seen that when the compressor is elevated, having carried the sash E' up with it, there is an open space between the inner upper edge of the packing-box A and the bottom of the compressor, through which space the cotton is blown into the packing-box.

When the compressor then descends, this space is closed by the sash, so that while the compressor is down in the packing-box, no cotton will be blown in on top of the compressor, but remain on the floor of the second story until the compressor is again elevated, and the sash raised, when the cotton thus collected against the outside of the sash is blown in, and falls down in the packing-box.

When the compressor C is elevated, the lint which

has fallen on the floor, intercepted by the sash, is blown from the gin into the box A, and again compressed as the follower descends.

This operation is continued until the packing-box is entirely filled.

The movement of the compressor is now stopped, and, if necessary, it is held in its place by pins at the sides of the box.

Then the screw E, worked by the crank F, by means of the drums G and H, connected by a band, I, drives the follower J upon the cotton until it is pressed to the desired dimensions, the follower J constituting, when in its proper positions, one of the sides of the packing-box A.

The whole power is contained in the main shaft d, turned by the crank F, which has four drums attached to it:

The drum G, connected by the band I with the drum H, for turning the screw E, so as to press the cotton.

The drum K, which is connected by a cross-band, L, with the drum M, for withdrawing the follower J, by turning the screw E in the opposite direction.

The drums H and M are placed on a hollow shaft, N, the gudgeon of which forms also the tap for the screw E, the tap being cut in the gudgeon; or, in other words, the gudgeon contains the tap through which the screw works, the screw passing up in the hollow shaft N.

The third drum, O, connected by a band to a drum or pulley, P, placed on the shaft to which the crank D is attached, thus turning said crank, and working the compressor C.

The fourth drum, which is intended to drive the gin in the second story, I have not deemed it necessary to represent.

The motive-power of the machine is the crank F, which may be worked by horse, steam, or water-power.

By means of the door R, in front and rear of the packing-box, the bale is removed from the press.

Grooves are cut into the sides of the press, to contain the ropes or bands to be used in tying the bale.

It will thus be seen that the double operation of ginning and pressing the cotton goes on at the same time.

It only requires one hand to superintend and work the machine.

There is no handling of the cotton after it is put in the gin, and it is packed perfectly clean, in regular layers, like batting.

This process gives perfect uniformity to the staple of the bale, which may be judged accurately by the smallest sample.

Having thus fully described my invention,

What I claim as new, and desire to secure by Letters Patent, is—

1. The combination of the box and frame A B, sash

E', vertically-acting follower C, horizontally-acting follower J, screw E, and hollow shaft N, with its drums H and M, all operating substantially as and for the purposes set forth.

2. The arrangement of the shaft *d*, turned by its crank F, with the drums G and K, connected, by means of bands, to the drums on the hollow shaft N, for operating the follower J; and a drum, O, for operating

the crank D, which works the compressor C, all substantially as shown and described.

In testimony that I claim the foregoing, I have hereunto set my hand, this 2d day of December, 1868.

J. J. MORRISON.
